SCREEN CASING FOR PORTABLE PICTURE SCREENS

Laurel E. Cooley, Sr., and Laurel E. Cooley, Jr., La
Grange, and Carl O. Plaul, Chicago, Ill.

Application May 25, 1956, Serial No. 41,659

Term of patent 14 years

Fig. 2 is a top plan view thereof.

Fig. 3 is a sectional view taken on the line 3—3 of Fig. 1.

Fig. 4 is a bottom plan view.

We claim:

The ornamental design for a screen casing for portable picture screens, as shown.
